UNITED STATES PATENT OFFICE

NICHOLAS STRAUSSLER, OF LONDON, ENGLAND

REISSUED

FOLDING VEHICLE

Application filed March 28, 1929, Serial No. 350,518, and in Great Britain February 13, 1928.

This invention relates to folding vehicles and is applicable to boats, perambulators, cycle side-cars, and similar vehicles, of the kind in which the floor of the vehicle has 5 one end curving inwardly at both sides towards the centre line or major axis and the other end truncated or squared, that is, formed at right angles to the said major axis, the side walls of the vehicle being continuously joined to the floor and following its contour, so that they can both be laid flat on the floor, while the stern or rear wall is similarly jointed at its lower edge to the floor.

10 According to this invention the lower edges of the side walls extend to the square end of the floor panel, and their top edges end some distance away from the top corners of the rear wall, stern or back-board, the gaps being triangular in shape, and triangular jointing pieces which may be of the same material as the floor and walls, extend between the sides of the undivided rear wall and the inclined portions of the side walls, 15 so that when erected they constitute portions of the side walls. The back-board can thus be conveniently laid down over the rear ends of the two side walls and over the triangular jointing pieces.

20 The vehicle may be constructed of material which possesses sufficient flexibility to enable the side walls to be bent at the front portion and the floor to rise in a curve corresponding with the curvature thus imposed on the side walls. This material may be plywood, with or without a coating of thin galvanized metal applied internally or externally, or both. The walls may be jointed to the floor by webbing treated with waterproof glue, or 25 by other suitable material.

In order that the said invention may be clearly understood and readily carried into effect, the same will now be described more fully with reference to the accompanying drawings exemplifying the application of the invention to boats.

Figure 1 is a side elevation and

50 Figure 2 is a plan of a boat opened out for use.

Figure 3 is a plan of the same boat collapsed.

Figure 4 is a plan illustrating a modification.

Figure 5 is a longitudinal section on a large scale taken on the line 5-5 of Figure 3,

55 Figure 6 is a cross section taken on the line 6-6 of Figure 3.

A indicates the flat bottom of the boat, B, C the side walls, D the stern connected with the side walls by triangular jointing pieces E, F. G indicates a grafting which can be placed across the boat bottom, H a hinge to which a rear seat (not shown), may be attached, J a hinge for the attachment of a front seat (not shown), K an eye through which any suitable hook may be passed to facilitate the lifting of the front end of the boat bottom in opening out the boat; M and N indicate U shaped clips for securing the ends of a pair of sculls which may be laid longitudinally of the boat when it is folded for storage or transport. W indicates the webbing which forms the joints between the relatively movable parts.

60 The rear wall or stern D is preferably narrower at its free upper edge than at its lower or jointed edge; when erected it may be vertical, or may be set to lean back. The lower or bottom edges of the side walls B, C extend to the square end of the floor panel A, whereas the top edges end some distance away from the top corner of the rear wall D, the gaps being triangular in shape. The triangular jointing pieces E, F which may be of the same material as the floor and walls, 65 extend between the sides of the rear wall on the one hand and inclined portions of the side walls on the other hand, so that when erected they continue the lines of the tops of the side walls to their junction with the upper corners or other parts of the rear walls, or may as illustrated in Figure 1 be slightly inclined downwards towards the stern.

70 In order to avoid the presence of a sharp point at the front of the vehicle, the gunwale or elbow rest in the case of a boat for example may be slightly inclined downwards towards the front, so that the side walls while rising to the full height of the back

wall leave a gap when laid down, as seen in Figure 4, and the floor may be rounded or truncated at this part.

A vehicle body thus constructed can readily be collapsed into a flat condition for storage or transit, and can readily be opened out when required for use.

What I claim and desire to secure by Letters Patent of the United States is:—

10 In a folding vehicle, a floor having one end curved inwardly at both sides towards the major axial line of said floor, the other end of said floor being straight and at right angles to the said major axial line, side walls continuously jointed to the sides of the said floor and following its contour throughout its length, said side walls being shorter at their upper edges than at their lower edges and being adapted to be turned down over 20 the floor and laid flat thereon with their normally upper edges towards the major axial line of the floor, an undivided rear wall continuously jointed at its lower edge to the straight end of the floor and adapted to be turned down over the outsides of the side walls when the latter are folded, and two triangular portions each jointed at one side to one side of the rear wall, said portions being each jointed at their forwardly inclined side 30 to an inclined edge of one of the side walls, whereby in collapsing the vehicle said triangular portions are caused to lie between the rear wall and the side walls.

NICHOLAS STRAUSSLER.
